CHARLES F. JENKINS, OF WILKINSBURG, PENNSYLVANIA, ASSIGNOR TO WESTINGHOUSE ELECTRIC & MANUFACTURING COMPANY, OF EAST PITTSBURGH, PENNSYLVANIA, A CORPORATION OF PENNSYLVANIA

ARMATURE WINDING

Application filed July 7, 1932. Serial No. 621,162.

My invention relates to a special armature winding and a stepped-slot core therefore, and it has special relation to such windings and core, for use in dynamo-electric machines of unusually large current capacity at relatively small voltages.

The principal object of my invention is to provide an armature core having stepped slots, the top portion of which is approximately twice as wide and half as deep as the bottom portion, and to provide an armature winding, cooperating therewith, composed of portions of uniform cross-section throughout its length, said winding being arranged with two portions or coil-sides disposed one above the other in the bottom portions of the stepped slots, and with two portions or coil-sides disposed side-by-side in the top portions of the stepped slots.

The same identical conductors which lie in the top part of the slot, continue around and occupy the bottom part of another slot, thus providing a stepped-slot construction without requiring the expedient of welding together two conductors of differently shaped cross sections.

The advantages, structural details, and applications of my invention are hereinafter described and claimed and illustrated in the accompanying drawing wherein:

Figure 1 is a front end view of a part of a core of an armature embodying my invention, with the end connections of one of the coils indicated in place, and with a cross-sectional view of the four coil sides or coil portions lying in place in some of the slots.

Fig. 2 is a top plan development showing the arrangement of the end connections.

Fig. 3 is an end view of the development shown in Fig. 2, and

Fig. 4 is a front elevational view of a few of the commutator bars showing the connection of the windings to the commutator necks.

In designs in which it is necessary to place as much copper as possible in the armature or rotor member of a dynamo-electric machine, a limitation has always been met, in the depth of slot which it is possible to utilize, on account of the reduction in the width of

the teeth between the slots at the bottom ends of the slots.

According to my invention, as shown in the drawing, I utilize an armature core 10 made up of punchings having stepped-slots 12 therein, and I utilize an armature winding made up of form-wound coils 14 which are of uniform cross-sectional shape and area throughout their lengths, and coil sides lying in superposed relation in the bottom of the stepped-slots 12, as indicated at 16, and lying in side-by-side relation in the tops of the stepped-slots 12, as indicated at 18.

The effect of such construction will be readily perceived when it is pointed out that, in an armature of ten-inch diameter, I have been able to use a depth of slot comparable to an armature of eighteen-inch diameter, by departing from the usual form of slot to one in which the two bottom coil sides 16 are disposed in superposed relation, the slots being only large enough to accommodate the coil sides 16 and 18, with their insulating coverings 20.

A further effect of the stepped-slot construction herein described is that it deepens the end windings 22 (Fig. 3), and thence shortens the length of copper taken up by the end windings. This is brought about by the fact that the end windings are disposed three-deep, as shown in Fig. 3, instead of being disposed two-deep, as would have been the case if the bottom coil sides 16 had been disposed in side-by-side relation instead of in superposed relation as shown in Fig. 1.

The drawing shows my invention applied to the armature member of a 15-kilowatt, 40-volt, direct-current generator. The coils are made from a rectangular copper strap, each coil consisting of two lengths of strap 90 which are connected in parallel. The coils are form-wound so that the bottom coil-sides 16 and the bottom front and rear end-connections 26 are disposed in superposed relationship, while the other ends of each strap, after the strap is formed into a coil, will be in side-by-side relationship, as indicated by coil sides 18 lying in the top sides of the slots and the upper end connections 28 at both the commutator end and the rear end of the armature. 100

The coils are formed with vertical or radial loops 30 near their middles, the loops being circumferentially displaced so as to make room for each other.

5 In the particular design shown, it is necessary for each coil to be wound so as to be made up, in effect, of two coils connected in parallel, the coils being connected together by silver solder 32 and spot welds 33, as indicated in Fig. 3.

I contemplate, however, that there will be certain uses or applications of my invention in which the part of the coils shown in Fig. 2 may be separate coils or they may be connected in series with each other rather than in parallel, the essential feature being that the coil sides under one of the field poles, at any moment shall be disposed in superposed relation, while the coil sides of the same pair of coils under the opposite field poles, at the same moment, are disposed in side-by-side relation, whether the coils are connected in series or parallel. In general, there may be any even number of coil-sides in each part of the slot, provided that there are twice as many coil-sides in side-by-side relation in the top part of the slot as in the bottom part, and twice as many coil-sides in superposed relation in the bottom part of the slot as in the top part.

In accordance with my invention, I also provide a novel form of connection of the armature coils to the necks 40 of my commutator bars 42, the commutator necks being furnished with stepped slots 44 for this purpose, with the distinction, however, that the top portions of the stepped-slots 44 each receive two armature-coil straps in side-by-side relation, whereas the bottom portions of these stepped-slots receive only one of the armature-coil straps, the bottom strap of the pair being cut off as indicated at 46 in Fig. 3, and being silver-soldered to the upper strap at this point, as indicated at 32.

45 I claim as my invention:

1. A dynamo-electric machine having a rotor member comprising a core having stepped slots, the top portion of the slots being approximately twice as wide and half as deep as the bottom portion, and an armature winding cooperating therewith, said armature winding being composed of portions of uniform cross-section throughout its length, said winding being arranged with two portions disposed one above the other in the bottom portions of the stepped slots, and with two portions disposed side-by-side in the top portions of the stepped slots.

60 2. A low-voltage high-current armature for a dynamo-electric machine, comprising a core having stepped slots, the top portion of the slots being approximately twice as wide and half as deep as the bottom portion, and an armature winding cooperating therewith, said armature winding being composed of a

plurality of coils, each coil comprising two form-wound straps of substantially uniform cross-sectional shape and area throughout their lengths, said straps of each coil being mechanically and electrically joined together at a plurality of points and so form-wound that the bottom coil-sides and the bottom front and rear end-connections are disposed in superposed relationship, the middle portions of the straps are in circumferentially displaced loops, and the top coil-sides and the top front and rear end-connections are in side-by-side relationship.

3. A low-voltage, high-current dynamo-electric machine comprising an armature core having stepped slots, the top portion of the slots being approximately twice as wide and half as deep as the bottom portion, and an armature winding cooperating therewith, said armature winding being composed of a plurality of coils, each coil comprising two form-wound straps of substantially uniform cross-sectional shape and area throughout their lengths, said straps of each coil being mechanically and electrically joined together at a plurality of points and so form-wound that the bottom coil-sides and the bottom front and rear end-connections are disposed in superposed relationship, the middle portions of the straps are in circumferentially displaced loops, and the top coil-sides and the top front and rear end-connections are in side-by-side relationship, and a commutator cylinder comprising a plurality of commutator bars provided with necks having stepped slots therein, the top portions of the neck-slots being approximately twice as wide, and of approximately the same depth, as the bottom portions of the neck-slots, the top front end-connections of the armature winding terminating in the top portions of the neck-slots, and the top strap of the bottom front end-connections of the armature winding terminating in the bottom portions of the neck-slots, the bottom straps of the bottom front end-connections terminating short of the commutator necks and being joined, near said termination to the respective superposed straps of the bottom front-end connections.

4. A dynamo-electric machine comprising an armature winding and a slotted armature core, characterized by the coil-sides of one pair of armature-winding coils being disposed in superposed relation in the bottom portion of one slot and in side-by-side relation in the top portion of a slot displaced substantially 180 electrical degrees from the first-mentioned slot.

5. An armature for a dynamo-electric machine, comprising a core having stepped slots, the top portion of the slots being approximately twice as wide and half as deep as the bottom portion, and an armature winding cooperating therewith, said armature

winding being composed of a plurality of coils made of form-wound lengths of strap-conductors of substantially uniform cross-sectional shape and area throughout their lengths, each strap-conductor being so form-wound as to produce two coil-sides lying in slots, and two front and two rear end-connections, with an integral radial loop joining the two rear end-connections, there being two shapes of coils arranged in pairs, each pair being such that the bottom coil-sides and the bottom front and rear end-connections are disposed in superposed relationship, the middle portions of the straps are in circumferentially displaced loops, and the top coil-sides and the top front and rear end-connections are in side-by-side relationship.

6. A dynamo-electric machine armature

comprising a core having stepped slots, the top portion of the slots being approximately twice as wide and half as deep as the bottom portion, and an armature winding cooperating therewith, said armature winding being composed of a plurality of coils each comprising one coil-side lying in the top portion of one slot and another coil-side lying in the bottom portion of another slot, characterized by an even number of coil-sides lying in each portion of each slot, there being twice as many coil-sides in side-by-side relation in the top portion of each slot as in the bottom portion of each slot, and twice as many coil-sides in superposed relation in the bottom portion of each slot as in the top portion of each slot.

In testimony whereof, I have hereunto subscribed my name this 16th day of June 1932.

CHARLES F. JENKINS.
